17 Inventor:
18 Thomas R. F. Potter,
by Walter E. Lombard, *Atty.*

UNITED STATES PATENT OFFICE.

THOMAS R. F. POTTER, OF BROOKLYN, NEW YORK.

SALES-CHECK HOLDER.

Application filed February 9, 1923. Serial No. 617,977.

To all whom it may concern:

Be it known that I, THOMAS R. F. POTTER, a citizen of the United States of America, and a resident of Brooklyn, in the county 5 of Kings and State of New York, have invented certain new and useful Improvements in Sales-Check Holders, of which the following is a specification.

This invention relates to devices for holding checks which have combined therewith means for notching the edge of a detachable check to indicate the amount of the sale, the object of the present invention being to provide a device of this character which 10 may be constructed cheaply and which will make a clean-cut notch in the edge of the check without tearing the material.

The invention consists primarily of a support for a pad of checks carrying a plate 20 adapted to be moved toward and from said support, said plate being provided with a flanged member forming a die having shearing edges and to which is pivoted a cutter member having cutting edges adapted to 25 coact with said shearing edges, said cutting edges being normally positioned above and at an angle to said flanged member or die, thereby permitting the insertion of a check which will have a clean-cut notch cut 30 therein when said member is moved toward said support.

The invention further consists in certain novel features of construction and arrangement of parts which will be understood 35 readily by reference to the description of the drawings, and to the claims to be herein-after given.

For the purpose of illustrating the invention, one preferred form thereof is shown 40 in the drawings, this form having been found to give satisfactory and reliable results, although it is to be understood that the various instrumentalities of which the invention consists can be variously arranged 45 and organized, and that the invention is not limited to the precise arrangement and organization of the instrumentalities as herein shown and described, except as required by the scope of the appended claims.

50 Of the drawings:

Figure 1 represents a plan of a device embodying the principles of the present invention.

Figure 2 represents a section of the same on line 2, 2 on Fig. 1. 55

Figure 3 represents an inverted plan of same.

Figure 4 represents an end elevation of the same, and

Figure 5 represents a plan of the die supporting plate and showing the die and cutter in plan. 60

Similar characters indicate like parts throughout the several figures of the drawings. 65

In the drawings, 10 is a rigid plate having upwardly extending side flanges 11 and the upwardly extending U-shaped rear end 12, in which is clamped in any well known manner the stubs of a pad of checks 13, 70 such as are used in restaurants, lunch rooms and the like.

These checks 13 are provided with a plurality of figures or other characters 14 adjacent to the edges thereof. 75

In order to indicate the value of a purchase, it is necessary to distinguish in some manner the proper character which is the equivalent of the amount of said purchase. This is usually done by cutting a notch in 80 the edge of the check opposite one of the characters 14, and until very recently these notches have been cut from the inside of the check outwardly. This method of cutting the notches very frequently causes the material of the check to be torn and leaves a ragged edge. 85

It has been found desirable, therefore, to cut the notches from the outside toward the interior of the check by two converging slits, 90 thereby producing a clean-cut notch.

The present invention relates entirely to means of making a clean-cut notch in the edge of the check.

To the rear end of the check support 10, 95 12 is secured at 15 a plate 16 bent downwardly so that the forward end is separated from the under face of the support 10. The forward end of the plate 16 is provided with an opening 18 therethrough, this opening 100 being triangular in outline with the apex of the triangle near the forward edge of said plate 16.

Secured to the upper face of the plate 16 is a member 19 having an upwardly extending flange 20 forming a die, the forward 105

end of which surrounds the opening 18 and is provided with shearing edges on its inner wall.

The rear portions of the flange 20 are parallel, and between these parallel portions of the flanges is positioned a cutter 21 secured to said flange by means of a pivot pin 22 extending through said cutter and the parallel portions of the flange 20.

10 The cutter 21 has a rearward extension 23 on which rests the free end of a spring 24, the opposite end of which is secured in position on the plate 16 by a bale 25 struck from said plate 16.

15 The spring 24 has sufficient tension to normally retain the curved upper face 26 of the front end of the cutter 21 in contact with the under face of the plate 10. The forward part of the flange 20 is of less height than the rear part thereof, thereby forming shoulders 27 which are adapted to limit the insertion of a detached check between the under face of the cutter 21 and the upper face of the forward end of the flange 20.

20 25 The forward end of the flange 20 is provided with shearing edges on its interior wall, which shearing edges are adapted to coact with the cutting edges formed on the forward end of the cutter 21, which forward end is shaped to accurately fit the interior wall of the flange 20.

When it is desired to cut a notch in a detached check, said check is inserted between the cutter 21 and flange 20 until its 30 edge abuts the shoulders 27. When this has been done, with the cutter 21 registering with the proper characters 14, the operator presses the forward end of the plate 16 toward the supporting plate 10. When this is 35 done, the curved face 26 being in contact with the forward end of the supporting plate 10, the cutter 21 will be forced about its pivot 22, causing the cutting edges of said cutter to coact with the shearing edges 40 of the flange 20 and a clean-cut notch will 45 be formed in the edge of the check.

50 It will be noted that owing to the angularity of the under face of the forward end of the cutter 21, relatively to the upper face of the flange 20, the formation of the notch will be accomplished by the successive cutting of two converging slits commencing at the extreme edge of the check and terminating at the apex toward the interior of the check. When the notch has been cut and the 55 detached check removed, the operator releases the plate 15 and the spring 24 will return the parts to their normal positions as indicated in the drawings.

60 Should the forward end of the cutter become slightly worn after constant use, the edges may be sharpened by removing in any well known manner a portion of the under face 27 of the forward end of the cutter 21, and in a similar manner the shearing

edges of the flange 20 may be sharpened by removing a portion of the upper face 28 of the flange 20.

This makes a very simple construction of check holder with an easily manipulated 70 notching device secured thereto, which, when operated, will always leave a clean-cut notch in the edge of a detached check.

The device may be made cheaply, and easily assembled, and when once assembled, it is impossible for it to get out of order except as its cutting edges may become dulled, in which case a ready means is provided whereby these cutting edges may be 75 quickly sharpened.

80 The cutter 21 being always positioned between the parallel sides of the flange 20, the registering of the forward end of the cutter with the shearing edges of the flange 20 is always insured. When the cutter is used to cut a notch in the edge of a detached check, the part removed from the check will be forced downwardly and pass through the opening 18 in the forward end of the plate 16.

85 It is believed that the operation and many advantages of the invention will be understood readily without further description.

Having thus described my invention, I 90 claim:

1. In a device of the class described, the combination of a support for a pad of checks; a plate secured to said support and adapted to have its outer end moved toward said support, said end having an opening 100 therein; and a pivoted cutter interposed between said plate and support with its cutting edges normally above said opening but adapted to enter said opening and coact with the wall thereof when the end of said plate 105 is moved toward said support.

2. In a device of the class described, the combination of a support for a pad of checks; a plate secured at one end to said support and adapted to have its outer end moved toward said support, said end having an opening 110 therein; a cutter pivoted to said plate, with its cutting edges normally above said opening and shaped to fit the wall thereof; and means coacting with said cutter for normally retaining the outer end of said cutter in contact with said support until by the movement of said plate toward said support, the cutting edges of the cutter are forced into said opening.

115 3. In a device of the class described, the combination of a support for a pad of checks; a plate secured at one end to said support and adapted to have its outer end moved toward said support, said end having an opening 120 therein; a cutter pivoted to said plate, with its cutting edges normally above said opening and shaped to fit the wall thereof; and a spring secured to said plate coacting with said cutter for normally 130

- retaining the outer end of said cutter in contact with said support until by the movement of said plate toward said support the cutting edges of the cutter are forced into said opening.
4. In a device of the class described, the combination of a support for a pad of checks; a plate secured at one end to said support and adapted to have its outer end moved toward said support, said end having an opening therein; a flanged member partially surrounding said opening; a cutter pivoted to said flanged member with its cutting edges normally above said flanged member with the inner wall of which the cutting edges of the cutter co-act; and means coacting with said cutter for normally retaining the outer end of said cutter in contact with said support until by the movement of said plate toward said support the cutting edges of the cutter are forced into said die.
5. In a device of the class described, the combination of a support for a pad of checks; a plate secured at one end to said support with its outer end movable toward said support and provided with an opening therein; a die secured to the upper face of said plate and provided with an upwardly extending flange, the inner front wall of which registers with said opening; a cutter member disposed within said die and pivoted thereto, with its cutting edges fitted to the inner wall of said die; and a spring for normally retaining the forward end of said cutter in contact with said support with its cutting edges above said die.
6. In a device of the class described, the combination of a support for a pad of checks; a plate secured at one end to said support with its outer end movable toward said support and provided with an opening therein; a die secured to the upper face of said plate and provided with an upwardly extending flange, the inner front wall of which registers with said opening, the forward part of said flange being lower than the rear part thereof, forming a shoulder to limit the insertion of a detached check; a cutter member disposed within said die and pivoted thereto with its forward end fitted to the inner wall of said die; and a spring for normally retaining the forward end of said cutter in contact with said support with its cutting edges above said die.
7. In a device of the class described, the combination of a support for a pad of checks; a plate secured at one end to said support with its outer end movable toward said support and provided with an opening therein; a die secured to the upper face of said plate and provided with an upwardly extending flange, the inner front wall of which registers with said opening; a cutter member disposed within said die and pivoted thereto with its forward end fitted to the inner wall of said die; and a spring for normally retaining the forward end of said cutter in contact with said support with its cutting edges above said die.
8. In a device of the class described, the combination of a support for a pad of checks; a plate secured at one end to said support with its outer end movable toward said support and provided with an opening therein; a die surrounding said opening; a cutter pivoted thereto provided at one end with cutting edges to coact with said die and at the opposite end with an arm having a depression therein; and a spring secured at one end to said plate with its opposite end in said depression, thereby normally retaining the cutting edges above and at an angle to the coacting shearing edges of said die.
9. In a device of the class described, the combination of a support for a pad of checks; a member carried by and movable toward and from said support; a die secured to said member having an upwardly extending flange with shearing edges at the forward end; a coacting cutter pivoted thereto and having cutting edges coacting with the shearing edges of said die; and means for normally retaining the cutting edges of the cutter above and at an angle to the shearing edges of said die.
10. In a device of the class described, the combination of a support for a pad of checks; a member carried by and movable toward and from said support; a die secured to said member having an upwardly extending flange with shearing edges at the forward end and provided with a shoulder to limit the insertion of a detached check above said die; a coacting cutter pivoted thereto and having cutting edges coacting with the shearing edges of said die; and means for normally retaining the cutting edges of the cutter above and at an angle to the shearing edges of said die.
